UNITED STATES PATENT OFFICE.

HENRY L. DOHERTY, OF NEW YORK, N. Y.

METHOD OF CARBONIZING FUEL.

1,207,723.

Specification of Letters Patent. Patented Dec. 12, 1916.

Original application filed November 15, 1911, Serial No. 660,450. Divided and this application filed January 29, 1915. Serial No. 5,110.

To all whom it may concern:

Be it known that I, HENRY L. DOHERTY, a citizen of the United States, and a resident of New York city, in the county of New York and State of New York, have invented certain new and useful Improvements in Methods of Carbonizing Fuel, of which the following is a specification.

This invention relates to a method of carbonizing fuel to convert tarry products of the same into gas.

This application is a division of my application Ser. No. 660,450, filed Nov. 15th, 1911, in which application I claim the broad features of the invention herein disclosed.

The object of my invention is to improve the manufacture of illuminating gas from fuels containing hydrogenous matter in retorts or the like by reducing the proportion of fuel required for heating the retorts, by taking the gas off of the retorts in a comparatively cool and pure condition, whereby the size of the apparatus required for the cooling and purification of the gas is diminished and the purification facilitated, by quenching and cooling the coke in the retort itself and at the same time returning and utilizing its sensible heat in the carbonization, by making it possible without change of apparatus to either recover the volatile tarry products of the coal separately from the main body of distillation gas or else to wholly convert the same into permanent gases and fixed residuum, as well as by the introduction of various minor features of treatment which will be described in detail below.

Briefly stated, my invention comprises the carbonization of fuel in elongated vertical chambers or retorts which are heated at a middle zone only, the portion of each retort above the said middle zone serving as a fuel preheating and tar condensing chamber, while the portion below the middle zone serves as a cooling chamber for the carbonized fuel.

The retorts are, during operation, always maintained fully charged—fresh fuel being charged in at the top as carbonized fuel is withdrawn from the bottom. The gases produced by the distillation of the

fuel in the middle zone are drawn off from the upper part of the retorts, and therefore through the mass of relatively cool fuel in the preheating chambers. The relative weights of fuel and gas will usually be such that the gas will be cooled down to at least 300° F., at which temperature substantially all of the heavy tarry matters of the gas will condense, the gas discharging comparatively cool and free from tar, but carrying water vapor and such light hydro-carbons as benzol, etc. The carbonized material is drawn down from the carbonizing zone proper into the cooling zone and there cooled by a current of gas or steam, or a combination of the two. For the cooling current it is advantageous to use a portion of the distillation gas itself after the removal of its illuminants and ammonia, together with more or less water vapor. The water vapor may advantageously be generated by the sensible heat of the gas as it is drawn off from the retorts and the latent heat of the water vapor which it carries. By evaporating the water directly into the deluminated gas returning to the retorts the evaporation may be carried out at a temperature below 212° F., by reason of the presence of the gas. The mixture of deluminated gas and water vapor passes up through the carbonized fuel in the cooling sections of the retorts, taking up the heat of the fuel and quenching the same, and at the same time facilitating the evolution from the carbonized fuel of the residual volatile matter which it contains. The returned gases then pass on up through the retort and join the main stream of gas which is being evolved from the fuel in the carbonizing zone proper. A portion of the volatile matter of the fuel is driven off from the same in the lower part of the preheating zone, by the comparatively hot gases from the carbonizing zone. When the tarry matters have accumulated in the preheating chambers to a degree which becomes objectionable, the flow of gas through the retorts is reversed—the cool returned gas being introduced at the top of the retorts and passed down through the tar-laden fuel in the preheating chambers, blowing the tarry liquid out of the interstices of the fuel therein and

carrying it down into contact with the hot coke in the lower part of the preheating region of the retort whereby the tar is re-vaporized. The returned gas laden with the tar vapors may be then either drawn off at a selected point above the carbonizing zone proper or else drawn down through the hot carbonized fuel in the said zone. In the former case the tar vapors may be again condensed, while in the latter case the tar is converted by the hot coke into permanent gases, difficultly-condensable hydrocarbons which may be utilized in the enriching of the distillation gas and fixed residuum which deposits in the coke increasing its density and hardness.

My invention also comprises various other features which are set forth below.

In this application I claim specifically the feature of the process, briefly described above, which deals with the method of operation in which the cool returned gas is periodically introduced at the top of the retorts and passed down through the tar-laden fuel in the preheating chambers to blow the tarry liquid out of the interstices of the fuel therein and carry it down into contact with the hot coke in the lower part of the preheating region of the retorts, to convert said tarry liquid into gas.

It will be seen that my process in part may be summarized in general terms as a process of heating and treating materials which comprises advancing material to, through and beyond a zone of high temperature, wherein changes in such material are accomplished, cooling the hot material beyond the said zone by a current of cooling gas, and bringing the gas thus heated into heat-transferring relationship to cool material advancing toward said zone.

In the drawings I have shown an apparatus embodying my invention and adapted to use in the carrying out of my process.

Figure 1 is a vertical cross-section through one of the beds of the bench with its coöperating gas producer on the line A'-B' of Fig. 3 and line A''-B'' of Fig. 4. Fig. 2 is a rear elevation of a portion of the bench showing the lower mouthpieces and the arrangement of the gas connections to the same. Fig. 3 is a partial plan of the apparatus. Fig. 4 is a horizontal cross-section through one of the beds and its coöperating furnace at the line A-B of Fig. 1. Fig. 5 is a vertical cross-section through a recuperator on the line E-F of Fig. 11. Fig. 6 is a horizontal cross-section of the same bed on the line C-D of Fig. 1. Fig. 7 is a detail view on an enlarged scale showing a side elevation of one of the gas off-take connections. Fig. 8 is an elevation of the screening device and fuel bin. Fig. 9 is a detail on an enlarged scale showing a portion of a fuel conveyer and the method of

discharging fuel from the same. Fig. 10 is a partial front elevation of the battery of producers. Fig. 11 is a horizontal section through the setting on the line I-J of Fig. 1. Fig. 12 is a vertical cross-section through the water evaporator. Fig. 13 is a detail showing a vertical section through one of the water distributors of the evaporator.

In the several figures, A, A', etc., are the retorts, 1, 1, etc., the carbonizing chambers of the retorts 2, 2, 2, etc., are the preheating chambers of the same 3, 3, 3, etc., the fuel cooling chambers of the same.

4 and 5 are, respectively, the rear and front walls of the bench shown in Fig. 1.

6, 6, 6, etc., are the gas-producing furnaces of the bench.

7, 7, etc., the fuel hoppers of the furnaces 6. 8, 8, etc., the discharging doors of the furnaces 6. The furnaces 6 have three distinct sections which may be designated as the preheating chambers, 9, the gas generating chambers, 10, and the cooling chambers, 11.

12 is a movable coke hopper and chute into which the mixture of fuel and ash drawn from the furnaces is received and from which it is gradually fed into the conveyer 13, which elevates the mixture to the screening device 14, from which the screened fuel passes to the bin 15.

16 is a bin for storing the raw coal used in the producer.

17 is a bin for the coal used in the retorts.

18 is a coal conveyer which is so constructed that it transports in turn both the fuel charge for the furnaces and that for the retorts.

72, 72, etc., are small lateral conveyers which receive the retort fuel from the conveyer 18 and transports it to the mouths of the retorts.

19 is one of the air recuperators of a bed, while 20 is the heat-interchanger of the same.

21 is a deluminator or scrubber in which the portion of the gas returned to the retorts is scrubbed with what is technically known as wash oil to absorb the illuminants from the gas.

104 is an ammonia scrubber through which the gas passes after leaving the deluminator 21.

22 is the hydraulic main which receives the normal gas from the dry mains 23. There is, as shown, one dry main for each row of retorts.

24, 24, etc., are the valves on the dry mains. 25 is an auxiliary hydraulic main which receives the gas drawn off of the retorts during reversal through the dry mains 26 or 27 according to whether the tarry matters are drawn off in the volatilized or permanently gasified condition.

116 is the water evaporator.

The method of operating my apparatus is

as follows: In starting operations fuel beds are built up in the furnaces by any preferred method. By one method coarse screened cinder is first charged into the furnace chambers until the coolers 11 have been filled. Fires are then kindled in the furnaces, air being supplied by the blowers 28. To permit this, the pipes 29 connecting the inlets of the respective blowers with the upper part 10 of the preheaters of the respective furnaces are each provided with a branch, 30, in communication with the atmosphere. By means of valves 31 and 32 the blower is put in communication with the atmosphere while the 15 connection to the top of the preheating chamber is cut off. Air in excess is thus forced up through the cinder in the coolers and supports the combustion of the ignited fuel thereabove. The products of combustion 20 pass off from the furnace through the regular gas off-take flues 33 to the equalizing flue 34 of the heat-interchanger 20, thence to the upcast flue 35. Passing up through 35 the gases go through the fan 36 and are 25 thence impelled down through the down-cast flue 37, which is separated from 35 only by the comparatively thin sheet-metal diaphragm 97. This, as shown, is built into the front wall of the producer. The flues 35 30 and 37 are formed by off-setting a sufficient number of bricks in corresponding vertical rows in the inner portion, 98, of the front wall of the producer. The metal sheet 97 is then set in place resting against the projecting bricks of 98, and extending a sufficient distance all around beyond the flue space 35 to prevent a flow of gas around its edges into flue 37. The outer portion, 99, of the front wall is then built at the same distance 40 from the sheet 97 as is the face of 98. Bricks, corresponding in position to the projecting bricks of 98, are off-set from 99 against the sheet 97. Around the outer margin of 97, the wall 99 is built directly against 45 the sheet 97, as is the wall 98. In the upper part of 97 an aperture is cut just the size of the gas inlet to 36 and corresponding to it in position when 36 is in place. There are thus formed two vertical flues, 35 and 37, 50 which are in communication with each other only through the fan 36. Since the initial temperature of the gas entering 37, in normal operation, will usually not be over 1500° F., and the character of the furnace gas will 55 be reducing rather than oxidizing, it is evident that either wrought iron, soft steel or cast iron may be used for constructing 97. While, it is true, that during direct combustion the gases are oxidizing in character 60 to sheet iron, their influence is not exerted for a sufficient length of time to be materially injurious to 97. Should the sheet 97 for any reason burn out, a new one may be put in position by banking the furnace, 65 temporarily permitting the gases generated

therein to escape to the atmosphere through 30, shutting off communication between the furnace and 35 by closing the flues 33 by the tile dampers 100, operated through the openings 101, tearing down the portion of the 76 wall 99 constituting the outer wall of flue 37, inserting a new diaphragm and rebuilding the wall. During the period of banking the flues 41 and 41' should be closed by tiles 102 (accessible through openings 103) to prevent 75 the indraft of cold air to the retort setting.

It is obvious that at the start of operations the gases will be subjected to a gradual cooling as they pass through the flues since the 80 setting is cold and contains more or less moisture. The gases therefore reach the fan at a lower temperature than that at which they enter the lower end of flue 35. Discharging from the periphery of the fan, 85 however, they are impelled down through the outer flue 37, and thus subjected to a re-heating by the hotter gases passing in the reverse direction through the flue 35. It is plain that a heat differential having once 90 been established between the two streams of gas, will thereafter be maintained indefinitely as long as no extraneous heating or cooling action is introduced. The amount of 95 this heat differential will, in the absence of any extraneous influence, depend entirely upon the superficial area and heat conducting power of the walls of the flues and upon the velocity of the draft. In any given case, however, within certain limits, should the 100 size of the flues 35 and 37 be too small, the normal differential may be increased by admitting an appropriate cold gas into the inner flue 35, through the pipe 38, which is, 105 in the construction shown, connected with the stack 39 of the recuperator 19, thus permitting the introduction of relatively cool combustion gases into the gas approaching the fan. The addition of the cold gas, of course, lowers the temperature of the gas 110 mixture reaching the fan and thus establishes the required heat differential between the two currents. In this case the differential is further increased as the gas flows back through 37 by the increased heat capacity 115 of the return current due to the volume of gas added. There is obviously no actual loss of heat from the gas (save the small loss to the setting) but simply a transfer of heat 120 from the current approaching the fan to the current discharging from the fan. By this device, therefore, I am able to move hot gases with ordinary fan blowers without any sacrifice of the heat of the gas. This invention, however, I do not specifically claim 125 herein, it forming part of another application.

From the flue 37 the combustion gases pass through the collecting flue 40 to the side flues 41 and 41'. From 41 and 41' the 130

gases flow into the transverse flue 105 and thence distribute themselves to the three combustion flues 43, 43, 43 through the ports 42. Flowing back through the flues 43 in contact with the walls of the retorts and setting the gases pass around the end of the horizontal baffles 106 in the flues 43 and thence forward through the flues 43''' to the front of the retort-oven, where they leave the oven through the gas off-takes 44, which communicate with the cross-flue 45. From 45 the combustion gases pass through the flues 112 and 112' to, respectively, the combustion gas flues 46 and 46' of the respective recuperators 19 and 19', through these, and finally discharging through the stack 39 to the atmosphere.

When the settings have been sufficiently dried out and heated, the apparatus is in shape to bring up to normal operating conditions. The fires in the furnaces are gradually increased in depth, the character of the gas changing gradually to a combustible gas containing carbon monoxid. When this stage has been reached, the air dampers 48 of the recuperators 19 are gradually opened, permitting air to flow through the air flues 49 of the recuperators, thence through the connections 113 and 113' and the flues 50 and 50' to either one or both of the cross-flues 109 and 109' and the respective sets of nostrils 51 and 51' into either one or both of the sets of combustion flues 43 and 43'. By means of the dampers 110 and 110' on, respectively, the connections 50 and 50', which connections establish communication between the flues 50 and 50' and the cross-flue 109, the distribution of the air between the flues 109 and 109' may be regulated at will. Operating rods 114 and 114', connected with 110 and 110' respectively, permit of the manipulation of the dampers. Since the walls of these flues 43 have been previously raised to the temperature of ignition of the combustible constituents of the furnace gas by the direct firing, the combustible constituents of the gas issuing from the ports 42 are burned by the air entering from 51. When the fuel bed has been built up above the primary current inlet 52, the remaining fuel required to fill the preheating chamber may be rapidly charged. The blowers 28 are now connected with the upper part of chamber 9 by shutting valves 32 and opening valves 31. A portion of the gases generated in the furnace 6 are now drawn by the blower 28 of each bed up through the fuel occupying the preheating chamber 9 of the furnace 6, whereby the said portion of the gases is cooled and the said fuel preheated. The portion of the fuel in the lower part of 9, when the charge contains bituminous coal, is carbonized, the distilled gases passing up with the stream of gases diverted from 10.

In passing through the fuel in the lower part of 9 any CO₂ or H₂O that may be in the diverted current is subjected in greater or less degree to reaction with the carbon of the incandescent fuel, thereby forming combustible gas. The cooled gas mixture is drawn off from 9 through the pipe 29 and thence forced through the pipe 29' into the lower part of cooler 11. Passing up through the fuel mass in 11, which has been subjected to partial combustion in the gas making zone 10, and therefore contains more or less ash, the gases introduced into 11 take up the sensible heat of the fuel mass, at the same time cooling the latter. By properly proportioning the volume of the gas introduced into 11 to the rate at which the solid material is withdrawn from 11 through the discharging door 8 the fuel and ash mixture may be thoroughly cooled before it has reached the discharging door 8. The heated gas passes upward through the fuel in the gas-generating chamber 10 and joins the main draft current of the furnace. At the same time that the pipe 29 is connected with the preheater 9, the speed of the fan 36 is increased and the various dampers set to provide the furnace with its normal primary draft. This, under normal working conditions, is composed of either partially burned gases drawn off from the flues 43', gases of complete combustion drawn off from the flues 43''' or of any mixture of the two required to regulate the working of the furnace.

In normal working, the furnace gas is not burned completely in the lower combustion flues 43, but the air admitted to the flues 43 from the nostrils 51 is restricted to that required to develop the quantity of heat which is demanded to maintain the proper temperature in the sections of the retorts in flues 43 and 43'. The balance of the secondary air that is required to secure complete combustion of the furnace gas is admitted by opening the air dampers 110 and 110' by means of the operating rods 114 and 114', respectively. A portion of the heated secondary air now flows through the short connections 113 and 113' to the upper cross-flue 109', thence through the air nostrils 51' into the partially burned gas which is flowing through the flues 43 to the rear of the bench. Enough air is always introduced through the nostrils 51' to insure the complete combustion of any unburned constituents remaining in the gases by the time they have reached the flues 43''. Since the inductive effect exerted upon the draft current in the combustion flues of the retort oven, by the stacks 39 and the fans 36, is greater in the flues 43'' than in the lowest combustion flues 43 the air will tend to flow from 50 and 50' through the connecting flues and

the nostrils 51' in preference to the nostrils 51. It is therefore only necessary to regulate the draft through the connections 113 and 113' by means of dampers 110 and 110' and the main air dampers 48 and 48' to secure complete control of the distribution of the air between 51 and 51'. By means of the dampers 110, 110' this distribution of the air is so regulated as to secure as uniform a temperature as possible throughout the combustion flues 43, 43', 43'' and 43'''.

The primary draft for the furnace is, in part, drawn off from the flues 43', by diverting a portion of the partially burned gas flowing through 43' through the nostrils 55 into the cross-flue 85 and thence through the flues 84 and 84' to the primary inlet flue 56 which discharges into the space 52 above the surface of the fuel in the furnace. Dampers 107 and 107' on 84 and 84', respectively, serve to regulate the volume of the partially burned gas withdrawn from the flues 43'. The balance of the primary draft current is made up of completely burned gases withdrawn from the main combustion gas flue 45 through the flue 47 in volume regulated by the damper 47'. The two portions of the primary current mingle in the inlet flue 56 and are drawn from 56 under the inductive action of the fan 36 into the space 52 in the chamber 10 above the surface of the fuel, thence the larger portion passes down and across the column of fuel in 10, emerging into the space 57 above the free surface of the fuel and pass through the gas off-takes 33 to the heat-interchanger 20, as already explained.

Both the portion of the primary current drawn off from 43' and the portion drawn off from the flue 45 are at a comparatively high temperature—from 2200° to 2500° F. While the initial temperature of the primary current is somewhat reduced by the time it reaches the furnace, still it should enter the fuel bed in the latter at a temperature above 2000° F., and usually at about 2200° F. In passing through the fuel bed in 10, more or less of the carbon dioxide of the primary draft and the water vapor carried by it react with the carbon of the fuel to form carbon monoxid and hydrogen according to the reactions

and

Both of these reactions absorb a large amount of heat, which is supplied by the sensible heat carried by the primary current at its entrance into the fuel bed, and sometimes by a portion of the sensible heat of the fuel itself. Since, by my method of combustion, the water vapor present in the gases is almost exclusively that derived from the air and fuel, its action in the fur-

nace is unimportant. We only need, therefore, to consider the action of the carbon dioxide. This reacts energetically with the carbon of the fuel at temperatures approximating 1800° F. and above, but less rapidly as the temperature falls. More or less reaction takes place even down to 1300°. It is evident, therefore, that by regulating the quantity of CO_2 carried into the furnace and the quantity of heat accompanying the CO_2 by regulating the draw of gases from 43' and 45, respectively, I am able to maintain the fuel bed in the chamber 10 of furnace 6 at any temperature desired within the working range.

In order to secure complete combustion of the gases in the combustion flues, it is necessary to introduce a slight excess of air into the flues from the nostrils 51'. The portion of the primary draft drawn off from 45, therefore, will usually contain a small proportion of free oxygen. This, of course, burns a corresponding quantity of fuel in 10 to form CO, with the generation of heat which helps to support the reduction of the accompanying CO_2 . Under normal working conditions, however, this excess of air is kept as low as possible. This portion of the draft current, therefore, has a strong net endothermic or heat-absorbing effect. The portion of the primary draft withdrawn from 43', on the other hand, carries under normal conditions more than enough sensible heat to dissociate its own CO_2 by reaction "a" and has thus a net exothermic or heating effect on the fuel bed. By varying the actual volume of the primary current and properly proportioning the two separate streams of gas making up the same I am able to control the temperature of the fuel bed in 10 and also the quantity of combustible gas generated. The volume of the gases drawn through the fuel bed is, of course, controlled by the speed of the fan 36 and the various dampers on the several conduits. This also serves to control the proportion of the CO_2 of the primary draft which is dissociated, since by varying the volume of the primary draft I vary the speed at which the gases pass through the fuel bed and therefore the time they are in contact with the hot fuel.

Contrary to the practice in producer firing, I do not aim to dissociate the maximum possible proportion of the CO_2 of the draft current in the furnace. On the contrary, in normal working the gases are circulated through the fuel at such a velocity that the dissociation is usually less than 50% of the total CO_2 that passes through the fuel. I am thus able to easily maintain the temperature of the fuel at a point that insures its maintenance in an active gas-making condition by the sensible heat introduced by the large volume of gases passing through it. My combustion process may therefore be com-

prehensively described as the maintenance of a continuous circulation of gases from the furnace to the retort oven and back again to the furnace—the return circulation to the furnace consisting of a balanced stream of completely and incompletely burned gases. A volume of completely burned gases corresponding to the air introduced into the combustion flues of the retort oven is continuously rejected from the circulation and sent through the air recuperator. By thus circulating a large volume of gases at high velocity through the combustion flues and the fuel bed of the furnace, as well as by distributing the combustion through the flues, I am able to secure the proper heating of the retorts without the necessity of maintaining an excessively high temperature in the combustion flues, since, as is well known, the velocity of heat transmission through the retorts varies with the velocity of the heating gases along the walls. No increased loss of heat in the rejected gases is occasioned, since the volume rejected from the circulation corresponds to the volume of air used and the two currents in the recuperators are thus about balanced in their thermal capacities.

The above described method of combustion I reserve the right to claim in a separate application.

The minor subdivision of the furnace gases passes up through the furnace shaft in contact with the fresh fuel in chamber 10. It is thus cooled while the fuel is at the same time heated—that in the lower part of 9 being carbonized. In passing through the short column of carbonizing fuel more or less of the reactive constituents of the minor subdivision of the primary current suffer dissociation. The gas passing through 10 therefore contains some CO as well as the volatile matters distilled from the coal. These latter are condensed by the cold fuel in the upper part of 9, being absorbed by the coke forming a large proportion of the charge and again carried down into the hot zone of the furnace. They are gradually evolved from the pores of the coke in contact with the hot coke and are more or less broken down into permanently gaseous compounds. A portion of this volatile matter may be again volatilized to be again condensed and carried down. This operation being repeated continuously until all the volatile matter is finally converted into non-condensable gases. The mixed gases are drawn off from 9 through the pipe 29 and forced by blower 28 into the bottom of the furnace. Being comparatively cold, they take up the heat of the fuel and ash in 11, quenching the fuel and cooling the mass. I aim to cool in 9 and introduce into 11 just the volume of gas required to quench and cool the fuel. Since at least about one-half of the charge consists of raw coal it is ob-

vious that the weight of material withdrawn from 11 will be much less than that charged into 9, for, besides the fuel burned, there is a diminution in weight due to the volatile matter and moisture driven off from the coal. The heat capacity required in the gas used for cooling the material in 11 will therefore always be less than that of the fuel charged in the same period of time. For this reason, sufficient cool gas to quench the material withdrawn from 6 will always be available.

The mixture of unconsumed fuel and ash withdrawn from the furnace at 8 falls into the bin 12 mounted on the truck 58. From 12 the material is gradually discharged onto the conveyer 13 and elevated to the screening apparatus 14. The mixture of fuel and ash is dumped into the hopper 59, and passes from this onto the grizzly or perforated screen 60. 60 is constructed with narrow apertures or slots of a width of not more than say $\frac{1}{4}$ inch. Air under a slight pressure enters the blast box 61 beneath the grizzly from the pipe 62. The air passing at high velocity through the grizzly, and the material passing over it, takes up the fine ash and carries it over into the ash pipe 63. The coarser particles of the ash, too heavy to be taken up by the air but fine enough to pass through 60, fall into the blast box 61 and are discharged from 61 at intervals by opening the gate 64. The two ash streams are conveyed away through 63 to a dump or directly to cars. The screened coke discharges from 60 through the chute 65 into the bin 15. The bin 16 receives the raw coal which forms part of the charge for the furnaces and which is delivered into 16 by the elevator 66. From the bins 15 and 16 the proper proportions of coked and raw coal are discharged onto the conveyer 18 and transported to the furnaces. The conveyer 18 as shown is usually an ordinary belt conveyer. The side wall of the conveyer (67) is provided with discharge openings 69 which are ordinarily closed by gates. These discharge openings are provided externally with short chutes, 70, so located as to discharge directly into the fuel hoppers 7 of the producers. When it is desired to fill the fuel hopper of any particular producer, the gate 69' above that hopper is opened, the dam 71 inserted in the conveyer chute above the belt and the conveyer started. When the fuel arrives at 69 the dam 71 diverts it into the chute 70 from which it falls into the fuel hopper 7 of that particular producer. When this is charged the gate 69' is closed and the same operation repeated with the next producer to be charged.

When charging the retorts the conveyer 18 receives the gas coal for the retorts from the bin 17 and discharges it onto the lateral conveyer 72 through the gates 73 in the wall 68

of the conveyer chute. The dam 71 is inserted into the slots 74 so as to divert the coal through 73 onto one of the conveyers 72. By setting the dams 71 at successively greater depths, several or all of the lateral conveyers may be used at the same time, as in this case the successive dams, up to the last, simply scrape each a shallow layer of coal from the conveyer 18. From 72 the coal is discharged into the open mouth-pieces of the retorts through arrangements similar to those used in the case of 18.

In starting operations, I prefer to charge the retorts A up to the chambers 2 with screened coke, the upper portions, 2, only being charged with coal. When the charge in the chambers 1 has been thoroughly heated up to the proper carbonizing temperature the system is in proper condition for establishing the normal circulation of the gas currents. Part of the cold coke or carbonized fuel in 3 is drawn, a corresponding volume of coal or other fuel descending from 2 into 1, and of hot carbonized fuel from 1 into 3, and the preheating chamber 2 is again charged with fresh fuel.

The height of the preheating chamber 2 will depend directly upon the rate of descent of the fuel mass, on the one hand, and the velocity of the heat-carrying gases, on the other. It is advantageous to have the preheating chamber of a height of from 5 to 10 feet, although this dimension may be varied more or less according to circumstances. The same statement holds true in the case of the cooling chambers 3, although the capacity of the coolers should generally be greater than that of the preheating chambers 2.

The gas evolved from the fuel during the carbonizing operation in the retorts is drawn off from the retorts through the Venturi throats 82 and connections 53 from the mouthpieces 54 to the dry mains 23 and passes thence through the conduit 22 (which may be a hydraulic main as shown) and the conduit 115 to the evaporator 116. This latter is simply a tubular vessel with apparatus for continuously distributing a thin film of water to each of the tubes 117. In the apparatus shown in the drawings this is accomplished by a short sheet-metal nipple 118, slightly belled and notched at its lower extremity so as to be held in the tube by the spring of the bell-shaped portion and at the same time permit of the discharge of the water through the notched periphery of the belled portion in a multitude of small streams which quickly converge to form a film on the inner surface of the tubes. The nipples 118, as shown, project above the upper tube sheet 119 of the evaporator 116. Water is supplied above the upper tube sheet at such a rate that there is maintained a small head of water upon the annular discharge openings 120 between the walls of

the tube and the nipples. The water should be supplied only at that rate at which it will discharge through the passages 120 so that it will not flow over the tops of the nipples. The gas from the conduit 115 enters the lower part of the intertubular space 121 of the evaporator and ascends through the same in contact with the tubes. The heat of the gas is thus transmitted through the walls of the tubes to evaporate the water flowing down the inner walls of the tubes. The temperature of the gas in flowing through 116 is reduced to such an extent that the water vapor and easily condensable hydrocarbon vapors such as benzol which it carries will be condensed and drawn off through the sealed discharge pipe 122. The hydrocarbons may then be separated from the water of the condensed liquid in the customary way by fractional distillation. The cooled gas discharges from 116 through the conduit 123 and flows to the exhauster 75. After passing 75 the gas divides into two streams—one stream passing to ordinary scrubbers and purifiers, while the other stream flows to the deluminator 21 through the connection 124. In this it is scrubbed with a liquid commonly known as "wash-oil" in the art which will absorb illuminants such as benzol, ethane, ethylene, etc. From 21 this stream of the gas passes through the ammonia scrubber 104, in which the ammonia is scrubbed out, and then flows back through the conduit 76 to the space 125 of evaporator 116 above the upper tube sheet 119. From 125 the gas flows through the tubes 117 in contact with the water flowing down the same, and is somewhat heated by the water. This gas serves to diminish the tension of the water vapor and so permits the water to evaporate below its normal boiling temperature. The surplus water is returned to the space 125 by the circulating pump 126 through the connections shown. While I do not restrict myself to this method of operation, I deem it advantageous to discharge the gas from 116 practically saturated with water vapor. Instead, however, I may either restrict the evaporation by limiting the quantity of water to that which I desire to evaporate or else by so increasing the quantity of water that its capacity for sensible heat below the evaporating temperature will be increased to the point which will leave available for evaporation only the quantity of heat corresponding to the latent heat of the quantity of water vapor which it is desired to form. If preferred, I may bypass the deluminated gas around the evaporator 116 through the by-pass 127 so that the cooling of the coke may be performed entirely by the deluminated gas.

The current of deluminated gas, either with or without the admixture of water vapor, flows back through the pipe 76 to the 130

main 77, from which the gaseous mixture is distributed to the dry mains 78, 78, etc., which run along each row of retorts and are respectively connected to the lower portion 5 of the cooler of each retort of the row with which they coöperate by the connecting passages 79. These passages 79 are each provided with a regulating valve and a Venturi meter, 81—the latter for giving an approximate 10 measurement of the volume of gas passing to the retorts. By this arrangement, it is possible to secure a very uniform distribution of the returned gas mixture among the several retorts irrespective of normal inequalities 15 in the permeability of their respective charges to the blast. Similarly, by means of the Venturi meters 82 and valves 83 on the off-take connections 53 at the top of the retorts I am able to secure an approximately 20 uniform draw of gas from the retorts irrespective of normal differences in the resistance to the blast offered by the charges in the several retorts. I therefore aim to control the draw from the retorts by carrying the hydraulic main 22 under a sufficiently 25 high vacuum to overcome the resistance to the draft offered by the most closely packed retort and regulate the draw on the other retorts by the flow of gas deduced from the 30 indications of the gage 82.

The cold deluminated gas or deluminated 35 gas and water vapor entering the bottoms of the retorts ascends through the material occupying the coolers, quenching and cooling this material and is itself heated. In normal working, the material occupying the coolers will, of course, be the coke residue from the coal carbonized in the upper zones of the retorts. The volume of cold deluminated 40 gas returned to the retorts should be such that the descending stream of coke and the ascending stream of gas will be approximately balanced in their respective thermal capacities. With this condition established, the coke will discharge from the 45 retorts at nearly the temperature of the cold gas, while the gas will, in turn, enter the carbonizing region of the retorts at approximately the temperature of the hot coke discharging from the same, or, in other 50 words, at about the temperature of carbonization. The returned gas in the carbonizing zone mingles with the gases and vapors evolved from the coal and the mixture and passes upward into the preheaters at approximately 55 the temperature of the partially coked coal in the upper part of the carbonizing zone. Since the maximum temperature to which the coal is exposed in the carbonizing zone is somewhat above 2000° F., the temperature in the upper part of the zone will usually be close to 1500° F. The upwardly flowing gas at approximately 60 this latter temperature will therefore extend the carbonizing action into the preheating

chambers at the expense of its sensible heat, since carbonization proceeds with considerable freedom even at a temperature as low as 750° F. The bulk of the easily condensable volatile matter will therefore be 75 driven off of the coal in the lower part of the preheating region since I have as the heat carrier to the fuel in the preheater not only the normal make of gas but the volume returned to the retorts also. This action 80 of the returned gas in reinforcing the action of the distillation gases as carriers of heat to the fresh fuel is an important function of the gas introduced into the coolers of the retorts.

The condensable vapors evolved in the carbonization will be taken up by the ascending stream of gas and therefore pass in contact with the cold fuel occupying the upper portion of the preheaters. The tarry 85 matter evolved in the distillation will therefore be deposited upon the coal occupying the upper part of the preheaters. The heat capacity of the combined gaseous stream is usually greater than that 90 of the coal charged, since, in order to cool the coke, the gas stream introduced at the bottom should itself have a heat carrying capacity of at least 70 per cent. of that of the coal. This is because in poor gas coals 95 the coke secured will usually run as high as 70 per cent. of the original coal distilled. Since there is not much difference between the specific heats of the coke and coal, and, moreover, the temperature from which it is 100 necessary to cool the coke is higher than the temperature to which the coal is usually heated in the preheating chamber, it is obvious that in this case at least 70 per cent. of the practical heat absorbing power of the 105 fresh coal will be required to cool the hot gases from the cooling chambers. When we add to this the heat of the distillation gases the combined gaseous streams will nearly always have a heat-carrying capacity 110 in excess of that of the fresh coal. The result of this is that the gases withdrawn at the top of the preheating chambers 2 will usually be at a temperature above 212° F. They will therefore carry out of the retorts 115 practically the whole of the water vapor and the benzol and allied compounds. On the other hand, the temperature of the gases drawn off will usually not be much over 300° F. and therefore nearly all of the ordinary tar-forming constituents of the gas will be condensed on the coal in the preheaters. The preheaters therefore fulfil to a large extent the function of condensers and the gas may usually be passed directly 120 to the purifying system without further cooling.

It is manifest that there will be a gradual accumulation of tar in the fuel in the preheater, since all of the condensed liquid 125

that finds its way down through the charge from the point of condensation will encounter a region having a temperature sufficiently high to revaporize it, when it will be again returned to the region of condensation. Unless special precautions are taken to handle the deposited tar, therefore, it will interfere seriously with the operation of the retorts by clogging the draft.

10 To dispose of the tar I adopt the following method of operation: When the deposit has accumulated to an objectional extent in any row of retorts, the valve 24 connecting the dry main 23 of this row with its hydraulic main 22 is closed, the valves 86 or 87 and 15 88 opened and the valve 89 on the deluminated gas main 78 serving that particular set of retorts closed. Deluminated gas or deluminated gas and water vapor, as the 20 case may be, under the pressure of the discharge side of exhauster 75 now flows from 76' through the pipe 90 and deluminated gas main 91 to the dry main 23 of this particular row of retorts and thence through 25 the connections 53 and 82 into the mouth-pieces 54 of the retorts, blowing the fuel column in the upper part of the preheaters free of tar, which is carried down into contact with the moderately hot partially coked 30 coal in the lower part of 2, whereby it is again converted, giving vapors and gases. If the valve 87 on the dry main 26 has been opened the gas, mixed with some of the vapors from the tar passes out from the retort through the connections 93 from the 35 upper part of the carbonizing chambers 1 to the dry main 26, thence to the hydraulic main 25, from which it is drawn by the exhauster 94, and from this to some form of 40 condensing apparatus, 200. If instead of opening 87 the valve 88 has been opened the gas bearing the revaporized tar is carried down through the highly heated coke, which in normal running fills the carbonizing 45 chamber 1, whereby the tarry vapors are "cracked" down into permanently gaseous hydrocarbons, carbon and hydrogen. The resulting gaseous mixture passes, in this case, through the connections 95 to the appropriate dry main 27 and thence to the hydraulic main 25, following from this the same course as the other stream of gas, just described.

50 Another important function of the reversal of the gas current is the prevention of an undue ascension of the hotter region in the preheaters 2 of the retorts. The returned gas being comparatively cold during its reversed flow cools down the coke in the 55 preheaters 2 and thus tends to drive down the isotherms of the retorts. By regulating the volume of gas returned during the reversals, therefore, I am able to control and regulate the temperature gradient in the 60 preheating chambers 2 to any desired extent.

With average coal and normal working conditions a reversal of the direction of gas flow for about one-fifth of the carbonizing period will usually suffice to keep the fuel clear for the free passage of gas. I 70 prefer to reverse for about one minute out of every five or six. It is, of course, obvious that both the duration of and interval between reversals will vary with the quality of the coal used, the temperatures 75 carried in the retorts, the weight of coal carbonized in unit time, and other minor conditions. It is obvious that by drawing off the gas from the retorts during reversals at selected levels I can secure a fractionating 80 of the tar.

The coke discharged from the chambers 3, 3, etc., being at practically atmospheric temperature, offers no obstacles to conveyance. Since I prefer to use the system of 85 operation in which frequent draws of coke of small quantities each are made, I may collect the coke drawn from each row of retorts in a car, 96, similar to 12, provided with a discharge chute, and, moving the car into the position shown, permit the coke to gradually discharge onto the conveyer 13, when that is not being used to convey the furnace coke and ash, and so carry it 90 to pockets or heaps.

In the operation of my apparatus, while this is not obligatory, I prefer to use the system of frequent small charges and draws, thus approaching to continuous operation. When preferred, however, the charging and drawing may be performed at longer intervals and on correspondingly larger quantities of material. No larger quantity of coke should ever be drawn, however, than that corresponding to the capacity of the 105 carbonizing chamber.

Instead of working intermittently as described, the operation of the retorts may be made absolutely continuous. Indeed, the fact that I remove the coke from the coolers in a cold state and that the fresh fuel is charged into a comparatively cold chamber makes my invention better adapted to continuous working than any other system of carbonization of which I have knowledge. To adapt my apparatus for continuous working it is only necessary to use mouth-pieces provided with a suitable apparatus, not shown in order to obviate complexity of 110 illustration, which will continuously withdraw the coke at the bottom and continuously charge raw fuel at the top.

An important feature of my invention is that instead of redistilling the tar formed in the original distillation of the coal in separate vessels I can, in effect, redistil it in the retort itself. The constituents of the tar which go to form pitch may be broken up in contact with the hot coke, depositing 115 the carbon thereby liberated in the pores of 120 125 130

the coke, after an operation similar to the one occurring in bee-hive ovens, whereby the hardness and density of the coke is greatly increased.

5 The principal factor of my invention in the production of a dense coke, however, is the height of the charge column. Owing to the relatively high column of fuel resting on the coal undergoing carbonization, 10 as compared with the height of the column in ordinary vertical retorts, the coal in the carbonizing zone is subjected to comparatively high pressure. This prevents the assumption by the coke of the light scoriaceous structure common in ordinary gas-house coke. By the combination of the two factors mentioned I am able to produce a coke comparable in hardness and density to that produced in bee-hive ovens and admirably adapted to metallurgical use.

An additional improvement in my method of carbonization that improves the quality of the coke in reference to size is the method of heating the retorts from two opposite sides only. To adapt the apparatus for carrying out this feature of my process it is best to construct the retorts with one horizontal dimension much longer than the other, the retorts being set in the oven with the wider faces of the walls parallel to the combustion flues. By this arrangement the coking proceeds simultaneously from the two sides toward the middle, since the heating of the end walls of the retorts is slower owing to the fact that what heat they receive must be by conduction through the thick brick fillings between the retorts. The lines of fracture produced by the shrinkage of the coke during its "setting", if that term may properly be used, therefore run across the fuel column from one heating face to the other. When the retorts are heated approximately equally on all four sides, on the contrary, there are lines of fracture 40 running between each two faces. These two sets of fractures necessarily intersect and thus divide the coke into fragments which usually show more or less uniformity in their cross dimensions. In this embodiment 45 of my method, on the contrary, the coke tends to form into large roughly prismatic pieces having a long dimension equal to half of the distance between the heating faces of the retorts. This quality of the coke is very advantageous from a commercial standpoint.

It should be noted that by taking up the heat of the coke in the gas introduced at the bottom of the cooler and then passing 50 the heated gas in contact with the cold fuel to heat the same I am in effect directly transferring the heat of the coke to the raw fuel since the mixture of the heated gas with the distillation gas does not materially affect the heat carried by the former. It

is true that the heated gas from the cooler does not reach the preheating chamber at quite the temperature at which it leaves the cooler since the temperature in the upper part of the carbonizing zone is somewhat lower than the temperature in the lower part thereof owing to the greater amount of distillation that is taking place there. The heat abstracted from this stream of gas, however, is applied to the heating 70 of the fuel. It therefore does not matter from the process point of view whether the heat transfer in question actually takes place in the preheating chamber or the carbonizing chamber. The practical result of the 75 operation is that the coke is not only quenched but that its heat, in excess of the initial temperature of the cooling gas, is wholly transferred, either directly or indirectly through the fuel to be carbonized 80 to the carbonizing region of the retorts.

Another important feature of my invention is the maintenance of the fuel column in a condition that will permit of the free and ready penetration of the gas current as a 85 result of the periodical reversal of flow described. The free passage of the gas is liable to be obstructed in two ways. First, the deposited tar in the column of raw fuel tends to fill up the interstices of the charge, reducing the area free for the passage of the gases; second, that part of the charge column which is in the immediate stage of carbonization tends to become pasty, the 90 fragments exhibiting a tendency to agglomerate to form a diaphragm across the charge column not easily penetrated by the blast. This diaphragm in a vertical retort takes the shape of an inverted cone, thus tending to force the gases evolved below it to the hot walls of the retort. This results in the cracking down of a serious proportion of the heavy hydrocarbons of this gas current, with a resulting diminution of the illuminating 95 power of the gas and a deposition of a shell of carbon around the inner walls of the retort. Now, during the normal flow of gas the pressure inducing flow is simply that corresponding to the vacuum in the hydraulic main 22. In ordinary working this is maintained as low as possible in order to reduce 100 to a minimum the infiltration of air. During reversal, on the other hand, the reversed gas is flowing under the induction of the vacuum in the hydraulic main and the positive pressure of the exhauster 75. Besides, the reversed current is flowing into the interior of the conical diaphragm which acts to throw the draft to the axis of the retort. The result of these two influences is that 110 115 the reversed current tends to force its way through the interior of the charge column, perforating the pasty diaphragm in a sufficient number of places to permit of its ready passage. Besides, the reversed current now 120 125 130

having the direction of the natural gravity flow of the tarry liquid readily blows this out of the interstices of the fuel column in the preheating chamber and bears it down 5 into the hotter regions of the retort where it is vaporized again. When the normal flow of gas has been restored, therefore, the fuel column is in a condition to permit of the free upward flow of the gas through its interior, until the above-described obstructions 10 have again formed, when the current is again reversed.

It is to be understood that my invention is applicable to the carbonization of any 15 carbonaceous material containing bituminous matter, and is not limited to use with gas or coking coals.

The method of conducting the combustion of the fuel in the furnace and of heating the 20 retorts I do not claim herein but claim specifically in another application.

I claim:

1. In the operation of a continuous vertical distilling apparatus for making gas and 25 coke, the process which comprises normally removing gas from the head of the coal column until tarry and pitchy matters accumulate in such column to an undesired extent and then forcing gas backward down 30 through said column until the desired amount of tarry and pitchy matter has been transferred downward into the coking zone.

2. The method of carbonizing fuel and making gas in a comparatively long conduit 35 having an intermediate localized externally-heated carbonizing section which comprises, charging the raw fuel into one end portion of said conduit, heating said fuel and distilling the volatile matter from said fuel in 40 said intermediate carbonizing section, passing the products of such distillation in contact with the raw fuel occupying the said end portion of said conduit, to condense tar-forming constituents of said distillation 45 products on said raw fuel, redistilling the so-condensed tar by periodically reversing the direction of flow of the gaseous products of the distillation to carry back the said tar into the said intermediate section of said conduit, 50 to vaporize the said tar, and withdrawing the so-revaporized tar from said chamber.

3. The method of carbonizing fuel and making gas in an elongated conduit having an intermediate localized carbonizing section which comprises, charging the raw fuel into one end section of said conduit, heating fuel and distilling the volatile matter from fuel in said intermediate section of said conduit, passing the gases and vapors from said 60 intermediate section in contact with raw fuel occupying the said end section of said conduit, to condense on the said raw fuel tar-forming constituents of the products of the distillation, periodically reversing the 65 direction of flow of the gas current passing

through said raw fuel, to carry back the/condensed tar in contact with the hot fuel in a intermediate section of said conduit and to re-vaporize the said tar, withdrawing the re-vaporized tar from said conduit and transferring the heat from the carbonized residue of said distilling operation to the said raw fuel.

4. The method of carbonizing fuel and making gas in a closed conduit having comparatively long end extensions which comprises, charging raw fuel into one end extension of said conduit, heating fuel and distilling the volatile matter from said fuel in an intermediate localized carbonizing section of said chamber, passing the gases and vapors from said carbonizing section in contact with raw fuel occupying the said end extension of said conduit, to condense tar-forming constituents of the products of the distillation of the fuel in said carbonizing section on said raw fuel, periodically reversing the direction of flow of the gas current passing through the raw fuel, to carry back the condensed tar, by means of the reversed gas current, into contact with hot fuel in the said intermediate section of said conduit and to re-vaporize the said tar, withdrawing the re-vaporized tar from said conduit, withdrawing hot carbonized fuel from said intermediate section into the other of said end extensions of said conduit, contacting with hot carbonized fuel in said end extension current of cold deluminated gas, to transfer to said cold deluminated gas substantially all the sensible heat of the said carbonized fuel above the initial temperature of said deluminated gas, and passing the heated deluminated gas in contact with fuel to be carbonized, whereby the sensible heat of the carbonized fuel is transferred to the said fuel to be carbonized.

5. The method of carbonizing fuel and making gas in a closed conduit having comparatively long end extensions and an intermediate localized carbonizing section which comprises, advancing a body of fuel through said conduit, the said body of fuel being advanced through said conduit and maintained in said conduit by withdrawing material from one end extension of said conduit and adding raw fuel to the other end extension of said conduit, heating said fuel and distilling the volatile matter from said fuel in said intermediate section of said conduit, passing the products of such distillation in contact with the raw fuel occupying the said end extension of said conduit, condense tar-forming constituents of said distillation products on said raw fuel, periodically reversing the direction of flow of the gaseous current to carry back the tar into the said intermediate section of said conduit in contact with hot fuel undergoing carbonization therein to re-vaporize the

tar and to convert heavy hydrocarbons of the tar vapors into difficultly condensable gases of lower molecular weights, and withdrawing the current of gas together with the 5 gases derived from the said tar from said conduit.

6. The method of carbonizing fuel and making gas in a closed conduit having comparatively long end extensions and an intermediate localized carbonizing section which comprises, advancing a body of fuel through said conduit, the said body of fuel being advanced through said conduit and maintained in said conduit by withdrawing 10 material from one end extension thereof and charging raw fuel into the other end extension thereof; heating said fuel and distilling volatile matter from said fuel in said intermediate section of said conduit, passing 15 gases and vapors formed in said intermediate section in contact with raw fuel occupying the said end extension of said conduit, to condense tar-forming constituents of the products of the distillation of said 20 fuel on said raw fuel, periodically reversing the direction of flow of the gas current passing through said raw fuel by introducing into the end extension of said conduit occupied by said raw fuel and passing through 25 said raw fuel a stream of relatively cool gaseous fluid to cool said raw fuel and to carry back condensed tar by the said gaseous fluid into contact with hot fuel in the said intermediate section of said conduit to re- 30 vaporize said tar and to convert heavy hydrocarbons of the tar vapors into simpler gases which are either permanent gases or difficultly condensable vapors, withdrawing 35 the gases introduced into said conduit together with the tar gases and vapors formed from said chamber and transferring heat of the coke residue of said fuel to a portion of 40 raw fuel.

7. The method of carbonizing fuel and making gas in a closed conduit having comparatively long end extensions and an intermediate localized carbonizing section which comprises, advancing a body of fuel through said conduit, the said body of fuel being advanced 45 through said conduit and maintained in said conduit by withdrawing material from one end extension thereof and charging raw fuel into the other end extension thereof, heating said fuel and distilling volatile matter from 50 said fuel in said intermediate carbonizing section of said conduit, passing gases and vapors from said intermediate section in contact with raw fuel occupying the said end extension of said conduit, to condense the 55 tar-forming constituents of the products of the distillation of said fuel in said intermediate section on said raw fuel, periodically reversing the direction of flow of the gas current passing through said raw fuel by 60 introducing into the end extension of said 65

conduit occupied by said raw fuel and passing through said raw fuel a stream of mixed deluminated gas and water vapor relatively cool to carry back the condensed tar by the reversed gas current into contact with hot 70 fuel in the said intermediate section of said chamber to re-vaporize said tar and to convert heavy hydrocarbons of the tar vapors into gases of lower molecular weight which are for the most part either permanent 75 gases of difficultly condensable vapors, withdrawing from said chamber at a locality within the carbonizing region of the same both the stream of introduced gases and the tar gases, restoring the normal direction of gas flow through said chamber, contacting with hot carbonized fuel from the carbonizing operation a current of cold deluminated gas, whereby substantially all 80 of the sensible heat of the carbonized fuel above the initial temperature of said deluminated gas is transferred to said deluminated gas and passing the heated deluminated gas in contact with fuel to be carbonized, whereby the said sensible heat of said coke is 85 transferred to the said fuel to be carbonized.

8. The method of carbonizing fuel and making gas in a plurality of substantially vertical conduits having comparatively long end extensions and intermediate localized 90 carbonizing sections, which comprises advancing a body of fuel through each of said conduits, the said bodies of fuel being advanced through said conduits and maintained in said conduits by charging raw fuel 100 into the upper end of said conduits and removing carbonized fuel from the lower end of said conduits, introducing a stream of deluminated gas and water vapor into the lower end of each of said conduits, conducting the said gaseous stream upward through the material in said vertical conduits, withdrawing gas from the tops of said chambers, periodically reversing the direction of flow of said deluminated gas and water 110 vapor, the said gas and water vapor during reversal being introduced at the tops of said conduits and withdrawn from localities within the intermediate carbonizing sections of said conduits.

9. The method of carbonizing fuel and making gas in a plurality of substantially vertical conduits having comparatively long end extensions and intermediate localized 115 carbonizing sections, which comprises advancing a body of fuel through each of said conduits, the said bodies of fuel being advanced through said conduits and maintained in said conduits by charging raw fuel into the upper end of said conduits and removing carbonized fuel from the lower end of said conduits, subjecting the fuel in the said localized carbonizing sections to a carbonizing temperature, introducing into the 120 lower extension of each of said conduits a 125

130

stream of relatively cool deluminated gas and water vapor, conducting said gaseous stream up through said fuel into the carbonizing section of said conduit, conducting the said stream of deluminated gas and gases evolved in the carbonization of said fuel upward in contact with the raw fuel in the upper extension of said charge column, withdrawing the said gases from said retorts near the mouthpieces of the same, removing a major portion of the illuminating constituents from a portion of said gases and reintroducing the deluminated gas and water vapor into the lower end extensions of said conduits, periodically reversing the direction of flow of said deluminated gas and water vapor, the said deluminated gas and water vapor during reversal being introduced into the upper end extensions of said conduits, conducting the deluminated gas down through the raw fuel in said end extensions and withdrawing the introduced gas and the gases generated in said retorts during reversal from localities within the intermediate carbonizing regions of said conduits.

10. The method of carbonizing fuel and making gas in a plurality of substantially vertical retorts having comparatively long extensions, which comprises maintaining a fuel body substantially filling each of said retorts, advancing said fuel body through said retorts by charging raw fuel onto the upper portions of said fuel bodies and withdrawing carbonized fuel from the lower parts of said fuel bodies, subjecting the fuel in the middle portions of the said fuel bodies to a localized carbonizing temperature, advancing the carbonized fuel into the lower end extensions of said retorts, withdrawing gas from the upper end extensions of said retorts, removing illuminants from a portion of the withdrawn gas, substantially saturating the deluminated portion of said gas with water vapor, introducing the mixture of deluminated gas and water vapor into the lower end extensions of said retorts, passing the said gaseous mixture up through the relatively hot carbonized fuel in the said lower extensions of said retorts, whereby sensible heat of said coked fuel is transferred to said stream of deluminated gas and water vapor, passing the heated deluminated gas and water vapor through the said carbonizing regions of said retorts, whereby illuminating constituents are again taken up by the said gaseous stream, passing the said gaseous stream and the gases evolved in the said carbonizing regions of said retorts up through the relatively cold raw fuel in the upper end extensions of said retorts, to condense the condensable vapors of said gases on said raw fuel, periodically reversing the direction of flow of said stream of deluminated gas and water

vapor, the said stream during reversal being introduced into the said upper end extensions of said retorts and passed down through the said fuel bodies to carry down the condensed matter into contact with the hot carbonized fuel to re-vaporize the said condensed matter and to cool said raw fuel, withdrawing the gas introduced and that formed in the retorts during reversal from localities in the carbonizing zones of said retorts, and restoring the normal flow of gas.

11. The method of carbonizing fuel in a plurality of vertical retorts having comparatively long end extensions, which comprises maintaining a fuel body substantially filling each of said retorts, advancing the said fuel bodies through said retorts and maintaining said fuel bodies in said retorts by withdrawing carbonized fuel from the lower portions of said fuel bodies and charging fresh fuel onto the upper portions of said fuel bodies, subjecting the fuel in the middle portions of said fuel bodies to a carbonizing temperature, to distil the volatile matter from said fuel, condensing the tar-forming constituents of the distillation gases by contacting the said gases with the raw fuel in the upper end extensions of said retorts, withdrawing the relatively tar-free gases from the upper end extensions of said retorts, and periodically carrying the condensed tar into contact with the hot fuel in the carbonizing regions of the retorts by introducing a stream of deluminated gas and water vapor near the tops of said retorts and withdrawing the gas introduced and the evolved gases from the carbonizing regions of said retorts.

12. In the carbonization of coal in a plurality of vertical retorts having comparatively long end extensions and intermediate localized carbonizing regions, the step which comprises periodically introducing into each of said retorts near the top of the same a stream of deluminated gas and water vapor under pressure, and forcing said streams downward through the upper portion of the fuel bodies in the retorts into the carbonizing regions of said retorts, whereby interstices are opened up in the interior of said charge columns which permit the free passage of the gases through said charge columns during the normal operation of said retorts.

13. In the carbonization of coal in a plurality of vertical retorts having a localized carbonizing region, the step which comprises periodically interrupting the normal discharge of gas from said retorts, introducing streams of deluminated gas under pressure into said retorts near the tops of the same, forcing said streams downward through the upper portions of the fuel bodies in said retorts into the carbonizing

regions of said retorts, to open up interstices in the interiors of said fuel bodies to permit of the free passage of the gases through said fuel bodies during the normal operation of said retorts, and exhausting the introduced gases and the evolved gases from the said carbonizing regions of the said retorts.

Signed at New York city in the county of New York and State of New York this 28th day of January A. D. 1915.

HENRY L. DOHERTY.
